ATTORNEY.

UNITED STATES PATENT OFFICE

114,294

DESIGN FOR A STOCKING

Louis H. Mendelsohn, Paterson, N. J.

Application February 28, 1939, Serial No. 83,263

Term of patent 3½ years

To all whom it may concern:

Be it known that I, Louis H. Mendelsohn, a citizen of the United States, residing at Paterson, in the county of Passaic and State of New Jersey, have invented a new, original, and ornamental Design for a Stocking, of which the following is a specification, reference being had to the accompanying drawing, forming part thereof.

In the drawing,

Fig. 1 is a front view of a stocking in partly folded state and showing my new design; and

Fig. 2 is a front view of the upper part of the stocking and on a larger scale.

The characteristic feature of the design resides in the ornamentation at the upper part of the stocking, as shown.

I claim:

The ornamental design for a stocking, as shown and described.

LOUIS H. MENDELSON.
